UNITED STATES PATENT OFFICE.

LUDVIG THORSEN, OF STAVANGER, NORWAY.

APPARATUS FOR SCRUBBING SHIPS' BOTTOMS BELOW THE WATER LEVEL.

Application filed June 2, 1922. Serial No. 565,324.

To all whom it may concern:

Be it known that I, LUDVIG THORSEN, a subject of the King of Norway, residing at Stavanger, Norway, have invented certain 5 new and useful Improvements in Apparatus for Scrubbing Ships' Bottoms Below the Water Level; and I do hereby declare the following to be a full, clear, and exact description of the invention, such as will enable others skilled in the art to which it 10 pertains to make and use the same, reference being had to the accompanying drawings, and to letters or figures of reference marked thereon, which form a part of this 15 specification.

The invention has for its object a self-acting apparatus for scrubbing ships' bottoms below the water level, while the ship is floating. The apparatus of this kind 20 hitherto constructed are complicated and are also connected with a great expenditure of power. The present apparatus is especially suitable to maintain the ship's bottom in a clean condition by frequent use, whereas it 25 is less suitable for the clean-scrubbing of ships' bottoms which are much covered with herbs.

According to the invention water under 30 pressure is used for driving the apparatus, said water placing by means of turbines brush rollers into rotation and producing simultaneously by its outflow from the apparatus the reaction force necessary to press the brush rollers against the ship's side, 35 whether the latter is vertical, inclined or horizontal.

The invention is illustrated in the accompanying drawing in which Fig. 1 shows the apparatus in plan. Fig. 2 shows the same 40 in side view. Fig. 3 shows diagrammatically the mode of operation of the apparatus. Fig. 4 is a detail sectional view of the distributing valve. The two brush rollers 1 and 2 may suitably be constructed as hollow metal rollers, upon which cylindric brushes are attached or sleeves of cocoa-mat 45 may be attached to these rollers. The rollers are toothed at both ends so as to fit with the flanges 3, 4 and 5, 6 respectively. 50 These flanges are fixed to pivots so as to be able to rotate in their bearings, the flanges 3 and 4 having thrust faces preventing their displacing in axial direction, whereas 5 and 6 may be released and displaced sufficiently 55 to release the toothings on the rollers 1 and 2, whereby the latter may be easily taken

out for changing brushes. The rollers 1 and 2 are provided with suitable arrangements for preventing rotation of the brushes on the same. Upon the roller pivots worm 60 wheels 8 are keyed which are in mesh with worms 10, the latter being fixedly keyed to spindles 12. On the other end of the spindles 12 running wheels for turbines 14 are keyed. The latter may be of any suitable 65 kind. The casings 15 and 16 enclosing the turbine wheels carry the conducting vanes and are cast integral with the casing enclosing the worm gear and they form at the same time bearings for the pivots on the 70 flanges 3 and 4. This casing is adapted to be screwed fast to the under frame of the apparatus. This frame consists of two buoyancy tanks 17 and 18 which also carry the bearings for the pivots 5 and 6. By 75 angle iron stays the tanks 17 and 18 are fixedly connected with an intermediate buoyancy tank parallel to the rollers.

The turbines have an inside supply, and the inlet pipes are fixedly connected with 80 the frame or buoyancy tank 19 and are bent outward, terminating at their outer ends in easily rotatable or swivel pipe couplings 20, 21, which are located on the same axial line. To these couplings the inlet pipes 22, 23 are 85 attached so that they may swing easily. The pipes 22, 23 are bent bow-like into the vertical central plane of the apparatus by means of the bends 24 and 25, in such a manner that the apparatus including the frame, 90 rollers, etc., may be turned freely about the axis of couplings 20, 21 between the pipes 22 and 23.

This bending takes place, however, as indicated in Figure 2, in two different planes 95 located symmetrically. Below the bends 24, 25 the pipes 22, 23 are bent further together to two adjacent points 26 and 27, and the plane through 24—26 and 25—27 coincides with the vertical symmetric plane of the apparatus.

At the points 26 and 27 the pipes are 100 fixedly joined at such a mutual distance that space is left for putting caoutchouc hoses 28, 29 upon each pipe.

To the bottom frame of the apparatus semi-cylindric plate screens 30 and 31 are 105 also attached (shown in Fig. 2, but not in Fig. 1). The same are concentric to the rollers 1 and 2 and leave a free space between the brushes and the screens. At the outward ends of screens 30 and 31 guide

screens 32 and 33 are arranged to direct material discharged by the brushes. The guide screens are intended to catch the water stirred up by the rotation of the brushes and throw it outward, so that instead of tending to wedge itself in between the brushes and the ship's side it has a tendency to assist in forcing the apparatus against the ship. To the screens 30 and 31 also the turbine outlet pipes 34, 35 are attached, which pass the water to the vertical symmetric plane of the apparatus. These outlet pipes discharge into jet nozzles 36, 37 which are inclined as is seen from Figures 1 and 2. The two hoses 28 and 29 attached together are passed up to a distributing valve 38 mounted on a small container, wherein is arranged an easily removable sieve and to which the rinsing hose of the ship is connected, the upper end of said hose being connected to the deck water conduit of the ship. Figure 4 is a sectional view of the valve and its connections with the hose pipes 28 and 29 and its two free outlet ports 39, 40, and its central valve body 41. This container with distributing valve 38 is adapted to be attached to the ship's work boat or tender or to a support which may be moved along a quay or the like. The distributing valve is provided with clear marks for angular positions of a handle for giving full water supply to both pipes 22, 23 or full water supply to one of them and partial water supply to the other one, or giving full water supply to one of them and none to the other one.

Besides, the different parts of the apparatus are so dimensioned that the weight of the apparatus—including the part of the hoses that must be carried by the apparatus—is practically equal to the buoyancy of the apparatus when in the water line. The size and location of the buoyancy tanks in relation to the weight and buoyancy of the total apparatus is distributed and balanced in such a manner that the apparatus is nearly in stable equilibrium, and only an inconsiderable reserve displacement will bring the apparatus to position itself near to the level, where the apparatus after being set out is left to itself.

The weight of the hoses and the pipe bow 22 and 23 will evidently cause these parts to hang downwards, and the symmetric plane of these parts will consequently always remain in vertical position, thus acting stabilizingly upon the apparatus.

According as the apparatus is being near to the water line or to the keel, its buoyancy will have to carry a greater or less part of the weight of the hose bight. This difference is balanced automatically by the fact that the plane sides of the buoyancy tanks are pressed in somewhat under the greater water pressure, whereby the buoyancy is

somewhat decreased. The plate thickness of the tanks is so calculated and dimensioned that it corresponds to this difference in weight.

The length of the hoses is so dimensioned in relation to the width, draught and bottom shape of the ship that the horizontal component of the weight of the catenary curve, even at the extreme position of the apparatus, does not surpass a certain maximum. The two turbines and worm gears are similar, but as they have opposite positions, they will cause opposite rotating directions of the two rollers 1 and 2 (see the arrows in Fig. 2).

An apparatus of this sort may be easily operated from the ballast donkey of a steamship. The operation of the apparatus will be understood from the above. The weight of the apparatus will be nearly balanced by the buoyancy with the exception that the weight of the pipe bow acts as a ballast and constantly maintains the centre line of the apparatus parallel to the water line. The apparatus will steadily be pressed against the ship's bottom by the reaction of the water jets forced out through the nozzles 36 and 37. Assuming the apparatus being arranged midships at the water line against a ship without lateral keels, but with a centre keel and assuming the roller 2 being stationary, whereas the roller 1 is supplied with power, then the apparatus will move downwards like a motor car, the path of which is the ship's side and the track of which is the rib line, its tractive pressure being equal to the component of the reaction force normal to the ship's side, its driving wheel being the roller 1 and its forward driving force being the component of the reaction force parallel to the ship's side plus the normal component of reaction force multiplied by a coefficient of friction. The resistance to this motion is, for a moderate advancing motion, comparatively small, and the consequence will be that the movement of the apparatus is accelerated until a corresponding resistance has been created on account of the velocity. Thereby an uncontrolled rapid forward feeding and consequently an incomplete scrubbing effect will result.

The velocity therefore must be retarded by giving the second (following) brush roller 2 a partial power supply, it being throttled to a suitable degree by means of the distributing valve 38. The opposite set of forces thereby formed may be so controlled that the same are causing at any time a suitable braking effect upon the running speed of the apparatus.

The running speed of the apparatus is suitably controlled by the operator having his attention directed to a thin rope, one end of which is attached to the apparatus and which is passing over a roll arranged at the

distributing valve 38, a small weight being attached (not shown) to the other end of the rope.

In this manner the apparatus is run down 5 until it strikes against the keel. Upon the end screens small cocoa mats are arranged, serving to fend off the shock and having simultaneously a scrubbing effect upon the keel.

By a small movement of the adjustable 10 handle of the valve the action of the two rollers is shifted, the roller 2 being now given full supply and being the leading one, whereas 1 is given a reduced supply and has a braking effect, and consequently the apparatus 15 moves upwards to the water line being constantly pressed against the same path which it followed during its downward motion. Upon the arrival of the apparatus to the water line the operator displaces the 20 apparatus through one roller length in longitudinal ship-direction, whereupon the work is continued.

Instead of producing a reaction pressure forcing the apparatus against the ship's side 25 directly by the reaction of out-flowing water jet, the pressure of this water jet may obviously also be utilized to cause indirectly the forcing of the apparatus against the ship's side, for instance by causing the water 30 jet to drive one or more propellers rotating in the surrounding water.

It has been formerly proposed to utilize the reaction of a water jet produced by a pump to press a scrubbing apparatus against 35 the ship's side. This arrangement is therefore not included in the features protected by the present patent.

Claims:—

1. In apparatus for scrubbing ships' bottoms below the water level by means of rotating brush rollers, the combination of brush rollers mounted parallel to each other in a frame, buoyancy tanks on said frame, turbines for rotating said brush rollers, 40 means for supplying water under pressure to said turbines, and means for causing the water leaving said turbines to press said rollers against the ship's side.

2. In apparatus for scrubbing ships' bottoms below the water level by means of rotating brush rollers, the combination of brush rollers mounted parallel to each other in a frame, buoyancy tanks on said frame, turbines for rotating said brush rollers, 45 means for supplying water under pressure to said turbines, and means for causing the water leaving said turbines to press said rollers against the ship's side, comprising jet nozzles with reduced outlet opening.

3. In apparatus for scrubbing ships' bottoms below the water level by means of rotating brush rollers, the combination of brush rollers mounted parallel to each other in a frame, buoyancy tanks on said frame, turbines for rotating said brush rollers in 50

opposite directions, means for supplying water under pressure to said turbines, means for causing the water leaving said turbines to press said rollers against the ship's side and means for imparting to one of said rollers an excess of speed for the purpose of imparting a movement to the apparatus. 70

4. In apparatus for scrubbing ships' bottoms below the water level by means of rotating brush rollers, the combination of two brush rollers mounted parallel to each other in a frame, buoyancy tanks on said frame, turbines for rotating said brush rollers in opposite directions, means for supplying water under pressure to said turbines, means for causing the water leaving said turbines to press said rollers against the ship's side and means for imparting to one of said rollers an excess of driving force, for the purpose of imparting a movement to the apparatus. 80

5. In apparatus for scrubbing ships' bottoms below the water level by means of rotating brush rollers, the combination of two brush rollers mounted parallel to each other in a frame, buoyancy tanks on said frame, turbines for rotating said brush rollers in opposite directions, means for supplying water under pressure to said turbines, and means for causing the water leaving said turbines to press said rollers against the ship's side 90

brush rollers, the combination of brush rollers mounted parallel to each other in a frame, buoyancy tanks on said frame, pipe couplings turnable about a common center line, passing through the common centre of gravity and buoyancy of the apparatus and carrying the water inlet pipes in such manner as to maintain by their gravity the brush rollers in positions parallel to the surface, turbines for rotating said brush rollers, means for supplying water under pressure

to said turbines, and means for causing the water leaving said turbines to press said rollers against the ship's side.

In testimony that I claim the foregoing ¹⁵ as my invention, I have signed my name in presence of two subscribing witnesses.
